UNITED STATES PATENT OFFICE.

JOHN HOFERLE, OF CHICAGO, ILLINOIS, ASSIGNOR OF ONE-FOURTH TO HENRY A. HOFERLE, ONE-FOURTH TO ANDREW AUER, AND ONE-FOURTH TO LOUIS AUER, ALL OF CHICAGO, ILLINOIS.

DOOR CHECK AND CLOSER.

1,115,539.

Specification of Letters Patent.

Patented Nov. 3, 1914.

Application filed December 26, 1912. Serial No. 738,558.

To all whom it may concern:

Be it known that I, JOHN HOFERLE, a citizen of the United States, residing at Chicago, in the county of Cook and State 5 of Illinois, have invented certain new and useful Improvements in Door Checks and Closers, of which the following is a specification.

This invention relates to improvements in 10 that class of door checks in which the resisting or checking action results from compressed air, and the door closing action is produced by a spring mounted in and forming a part of the complete device, thus providing a combined door-check and closer.

Aside from providing a simple, compact, economic and effective pneumatic door check, an important object of my invention is to provide means whereby the same check 20 may be directly connected to the door frame, and with right or left-hand doors, without changing the form of the attachments.

A further object of my improvements, is to provide means by which the speed at 25 which the door is closed may be easily regulated.

A still further object of my improvements is to provide a swivel connection between the check and its support which will be both 30 adjustable and flexible, thus adapting the device to variations in contour, position and arrangement of the door and door frame to which it is attached.

I have shown a preferred embodiment of 35 my invention in the following views:—

Figure 1 shows my improved door-check and closer mounted in position contiguous portions of the door and door frame being shown; Fig. 2 is an enlarged longitudinal 40 vertical section of the cylinder and the parts mounted therein, which form important features of my invention. Fig. 3 is a top-plan view of the complete device shown in Fig. 1, showing its operative position when the 45 door is partly open; Fig. 4 is an enlarged detail, partly in section, of the supporting bracket and the cylinder engaged thereby; Fig. 5 is a perspective view of a socket plate

adapted for use with the cylinder of my improved check, under certain conditions. 50

Referring to the details of the drawing, 6 represents a metal cylinder or pipe threaded externally at its ends, as at 6^a, 6^b, to which are fitted caps 7, 20, respectively.

On the outer face of the cap 7 is a boss 7^a 55 which is tapped to receive a screw 8 which is cut away on one side, as at 8^a, to form a graduated passageway for air from the interior of the cap or cylinder to the atmosphere, said screw serving therefore as a 60 valve.

Projecting inwardly from the cap 7, is a hook 9 the outer end of which is headed over as at 9^a. Connected with the hook 9, is an expansion coil spring 10, the opposite end of which is connected with a similar hook 11, 11^a, secured to a cup-shaped casting 12 which is internally threaded at 12^a, and is formed with spaced parallel lugs 12^b in which are holes 12^c. The threads 12^a engage male threads on one end of a tube 13 which extends through an opening 20^a in the cap 20, into the cylinder 6. This tube is but slightly shorter than the cylinder 6, and to its inner end are secured collars 14, 15, between which is clamped a cup-shaped piston ring 16, of leather or other suitable material, which has a snug but sliding fit to the walls of the cylinder 6. 70 75

A short distance from the cap 7, spaced 80 holes 17, 18, are formed in the wall of the cylinder 6, and are covered and connected by a housing 19 secured to the outer wall of the cylinder, said holes and housing forming a by-pass for a purpose to be disclosed. 85

Secured to the door A, near its top, by screws 23, is a bracket consisting of a plate 21 and a stud 21^a, the latter perforated transversely to receive a bolt 22, which also passes through the holes 12^c in the lugs 12^b 90 and thus connects the bracket with the cup-shaped member 12.

A split collar 24 (see Fig. 4) embraces the cylinder 6, and is adjustable thereon by loosening the screw 25 which passes through 95 threaded openings in the ears 24^c of the col-

lar. The collar is formed with a circular boss 24^b which is formed concave in its outer face and externally threaded as at 24^a, to engage the internal threads of a cup-shaped collar 26^b. This collar with the concave recess in the boss 24^b forms a socket in which loosely fits the rounded end 26^a of a short rod 26 which is inserted in the outer end of a pipe elbow 27 which, in turn, engages a short section 28 projecting from a cylindrical bracket 29 having a flange 29^a by which it may be attached by screws 30 to a door frame lintel C, as shown in Fig. 1.

In some instances, the angular fitting composed of the members 27, 28 and 29, may be dispensed with, and that shown in Fig. 5, substituted. This fitting consists of a casting having a circular base 31 in which screw-receiving holes 31^a are formed, and from which rises a conical projection 31^b, which is internally threaded as at 31^c so that it may be screwed directly upon the member 26.

The operation of my improved check is as follows:—Assuming that it is desired to close and check the door A, hinged to the jamb B, and having a lintel C, the bracket 21 is screwed to the top rail of the door A, and the bracket 29 is screwed to the lintel, at about the relative positions shown in Fig. 1. The member 12 is then connected by bolt 22 with the bracket 21, the collar 24 is adjusted to the cylinder and clamped thereon, and the valve 8 turned so as to admit air through the nipple 7^a to the interior of the cylinder 6. Upon the door A being moved to open position, the cylinder will swivel on the connections 24, 26, the tubular piston stem 13 will be drawn outwardly from the cylinder 6, and the spring 10 will be expanded. As the piston 16 moves toward the cap 20, air will enter the cylinder through the port 7^b, and occupy the space between said piston and the cap 7. As soon as the door is released, the contraction of the spring 10, will cause it to move toward the closed position, in which the return movement of the piston will be resisted by the more or less compressed air cushion between said piston and the cap, plus atmospheric pressure at the vent or port 7^b. As the latter is small in area, the air, will escape slowly until the piston reaches a point between the ports, 17, 18, when the air will rush through the by-pass 19 and past the piston, to the other portion of the cylinder chamber, where, by reason of the opening 20^a in the cap 20, there will be only atmospheric pressure, thus accelerating the return stroke of the piston and closing the door with sufficient force to insure the latching operation of the usual lock.

It will be noted that the swivel movement

of the cylinder, will maintain it at a proper angle to the plane of movement of the outer end of the piston-tube 13, so there will be no lateral strain on the latter. If the door, in its swinging movements, shculd sag or drop slightly because of a loose hinge connection D with the jamb B, the cylinder 6 will tilt downwardly at its end adjacent the door, this movement being permitted by the loose connection provided by the ball and socket joint at 24^b—26^a—26^b, and thus any strains that would otherwise result will be avoided.

Having thus described my invention what I claim as new, is:—

1. In a device of the character described, a bracket, a cylinder supported from said bracket, a piston slidably mounted in said cylinder, a tubular piston stem, a coil spring arranged in said piston stem and adapted to be expanded by the outward movement of said piston stem, means whereby said piston stem will be moved outwardly, a valved opening into said cylinder and a by-pass outside the walls of said cylinder.

2. In a device of the character described, a bracket, a cylinder, a universal jointed connection between said bracket and cylinder, a piston slidably mounted in said cylinder, a tubular piston stem, an expansible coiled spring arranged in said stem and connected at one end with the cylinder, and at the other end with said stem, means whereby said stem will be drawn outwardly, an adjustable valve controlling an opening into said cylinder, and a by-pass outside the walls of said cylinder.

3. In a device of the character described, a bracket, a cylinder, an adjustable and swiveled connection between said bracket and cylinder, a piston slidably mounted in said cylinder, a tubular piston stem, an expansible coil-spring arranged in said stem and connected at one end with the cylinder and at the other end with said stem, means whereby said stem will be drawn outwardly, and an adjustable valve controlling an opening in the other end of said cylinder.

4. In a door check and closer, a cylinder, a supporting means, a ball and socket joint connecting said cylinder and said supporting means, a piston mounted at the end of a tubular piston stem within said cylinder, an expansible coil-spring arranged within said stem, and connected at one end thereto, and at the other end to said cylinder, a valve controlling an opening into said cylinder, and a by-pass outside the walls of said cylinder.

5. In a door check and closer, a cylinder, a supporting means for said cylinder, a horizontal adjusting means connecting said cylinder with said supporting means, a pis-

ton mounted at the end of a tubular piston stem within said cylinder, an expandible coil-spring arranged within said stem and connected at one end thereto, and at the 5 other end to said cylinder, and a by-pass outside the walls of said cylinder.

In testimony whereof I affix my signature in the presence of two witnesses.

JOHN HOFERLE.
